[57] CLAIM

The ornamental design for an adjustable pipe clamp, substantially as shown and described.

DESCRIPTION

FIG. 1 is a perspective view of an adjustable pipe clamp showing our new design;

FIG. 2 is an enlarged front elevational view thereof;

FIG. 3 is an enlarged rear elevational view thereof;

FIG. 4 is an enlarged left side elevational view thereof, the right side being a mirror image;

FIG. 5 is an enlarged top plan view thereof; and

FIG. 6 is an enlarged bottom plan view thereof.

The pipe is shown in broken lines for illustrative purposes only.
